Application March 25, 1941, Serial No. 385,162

8 Claims. (Cl. 274—23)

This invention relates to sound recording and reproduction. The instrument embodying the elements of the invention provides means for recording sound on or reproducing sound from a plurality of records.

One of the objects of the invention is to incorporate a push-pull principle in a plurality of sound heads mounted on a tone arm to reduce surface noise of the phonograph needle in riding against one side of the groove on a record.

Another object of the invention is to provide means whereby sounds may be recorded or reproduced on a plurality of records to effect a composite result found useful in a number of professions, including the teaching and medical.

Other objects of the invention will become apparent from a careful study of the hereunto annexed specification and drawings, in which drawings:

Fig. 1 is a top plan view of the double arm assembly in operative position over two records;

Fig. 2 is a side elevation of the instrument shown in Fig. 1;

Fig. 3 is a cross section of details of the central pivot and elevating means for the tone arm assembly;

Fig. 4 is a sectional view similar to Fig. 3, taken at right angles to the latter;

Fig. 5 is a perspective view of a detail of the device to limit movement between the two sections of the tone arm;

Fig. 6 is a schematic diagram showing two record holders operated by a single motor; and

Fig. 7 is a schematic diagram showing two record holders each driven by an independent motor.

The essence of this invention comprises the phonograph recording or reproducing arm of a duplex type. A composite pivoted arm is provided which has a sound head mounted at either end of the arm, the heads being readily replaced by either a sound recording or reproducing head, depending on what is desired at each end of the arm.

Refinements are incorporated in the structure which permit adjustments of several kinds that will be described later, which permit the structure to be utilized advantageously in the following respects.

By using the instant invention it is possible to reproduce two different kinds of special sounds simultaneously, such as a vocal solo on one record and an orchestral accompaniment on another record, and from the two reproductions a composite record may be made on a third record.

Similarly, a conversational record may be reproduced simultaneously with a record having other accompanying sounds, such as those of birds, insects, whistles and the like, and a composite record made of the recordings of both of the first records.

As another example of the use of the device, in an orchestral reproduction two blank records may be utilized, one beneath each of the sound heads which, in this instance, will be recording heads, and one head will be made responsive particularly to low notes or to a special group of instruments and the other head will be set responsive particularly to high notes or a still different special set of instruments. The two records thus made may then be played simultaneously in a twin reproducer of the character of this device and this simultaneous playing may be broadcast as a composite selection or the simultaneous playing may be recorded on a third record for future playing or broadcast. One object for this is that it has been proven that the difference in volume obtained from two records feeding into one amplifier is increased approximately 5 to 10 decibels over the summation of the sound from two individual records not played simultaneously, and the distinctness and separation of the musical scores and voices will be reproduced with greater fidelity.

It therefore is obvious that much greater amplification can be afforded from a phonograph record source utilizing two records each reproducing different parts of a composite program, in contrast to where only a single record is used to reproduce the total composition.

Also in the teaching of singing, it is possible to furnish the student with a complete orchestral reproduction through a high fidelity reproducing system and such a record may be played on one record holder of the applicant's device and a reproducing head fitted to cooperate with this record, while on the other record holder a blank record is provided and a recording head fixed to the corresponding end of the tone arm so that a pupil may sing into an independent microphone, the blank record recording both the orchestral selection and the voice of the pupil.

In this connection it is possible to arrange the applicant's device whereby the voice may be recorded independently rather than having a composite record of voice and orchestra both, in which instance corrections may be made in the record being made of the voice and the record on which the recording is made may be played back, using the twin phonograph arm, on replay-

ing, to determine whether the mistake has been satisfactorily corrected.

Still another important use of applicant's invention is found in instructing the deaf, with a view toward improving their natural hearing, particularly where such teaching is done in classes through a sound source. In order that a wider range of the class may be accommodated, two identical records may be played on the applicant's device, one being set louder than the other. The students in the class, being deaf in varying degrees, will hear through earphones whichever record is closer to their perceptible pitch, and thus a larger range of the class may be reached.

In this same connection various combinations of overtones, harmonics and independent combinations of sound on a single record may be formed into a composite result which may be added to or detracted from by the exchange of records to suit the particular progress that the deaf patient has reached at the particular time of treatment, and as their hearing improves from time to time, another combination of these sounds may be made by suitable combinations of the proper records.

In further explanation of this, for instance, a record is formed having a train whistle. A train whistle is heard by people with normal hearing in combination with many other sounds, such as a locomotive or moving train, and any reverberated sounds that are created by the movement of the train. To a deaf person it is of distinct value to bring about the ability to understand all of these independent sounds in combination with one another and gradually learn to discriminate between them all. In the earlier treatment only a very few of the basic noises are used, whereas as treatment progresses, more complex combinations of these noises are brought into play and a wide range of possibilities of the combination of such noises is permitted by using the instant invention, together with suitable records for the purpose. In passing, it might be said that the applicant has provided a device that has wide possibilities in affording treatment for improving the hearing of deaf or partially deaf persons and has provided substantially thirty different compositions of records which are available for prescriptions in treating such persons with impaired hearing.

This invention, however, mainly embraces the mechanism for mounting the tone arms in relationship with the records, as distinguished from the treatment effected by using the device, and therefore a more detailed description of the mechanism follows:

One of the important advantages of the invention resides in the reduction of the surface noise of the phonograph needle proper which tends to ride against one side of the groove of the record. In the applicant's device this is offset to a large extent by what may be termed a "push-pull" principle. The record holders are rotatably mounted on pivots and the pivot for the tone arm is substantially in line with these two pivots. The tone arm is arranged crosswise of the line of pivots, whereby as the head on one end of the arm is fed inwardly, the head on the other end of the arm will also be fed inwardly on the other record, and in the feeding of the needles inwardly, the ends of the arms will impress substantially the same identical drag upon each other while the needles are in the grooves, to cause more flexibility in balance between the two arms.

This is brought about by the fact that if the needle in one end of the arm tends to push against one side of the groove, the needle on the opposite end of the arm will have a drag impressed on it by such pushing and thus tend to bring the first needle back to the center of the groove.

As shown in Figs. 1 and 2, a composite tone arm 10 is pivotally mounted about a standard 11, the details of the pivoting means comprising a tubular member 12 secured to the arm 10. A cam 13 is pivotally mounted in the upper end of the tubular member 12 about a pivot 14. A concave seat 15 is provided at the top of the standard 11 and a ball bearing 16 is seated therein. The surface of the cam 13 engages the ball bearing to raise and lower the tubular member 12 and tone arm affixed thereto.

Surrounding the tubular member 12 is a cylindrical element 17 which is fixed to the standard 11 by means of a threaded lug 18. The tubular member 12 and the arm 10 may move vertically with respect to the standard 11 and the cylindrical element 17 since a slot 19 is provided in the tubular member 12 in which the threaded lug 18 may move.

The tone arm 10 is actually composed of two parts 20 and 21. The part 20 is longer than the other and the tubular member 12 is secured to this part. Shorter arm 21 is pivoted to the longer arm 20 by means of a vertical shaft 22 which is arranged in suitable apertures in the frame of arm part 20 and ears 23 provided in arm part 21 are also suitably apertured to engage the pivot 22.

Mounted on the upper surface of arm 21 is a resilient member 24 suitably secured by screws 25 at one end. The opposite end of resilient member 24 is formed generally as an annulus to provide a loop 26 surrounding the cylindrical element 17. The inner diameter of the loop 26 is larger than the outer diameter of the cylindrical element 17, whereby a limited amount of movement may be afforded the arm 21 about the pivot 22.

The outer end of the loop 26 is formed with an element having a depending notch 27 which engages lug 18. The amount of play afforded the resilient member 24 is controlled by the threaded screw 28.

To summarize the operation up to this point, when the cam 13 is swung to the position of Fig. 4, both parts 20 and 21 of the duplex tone arm are raised, and are held in the raised position by the locking action of the cam; at the same time, loop 27 is raised into engagement with lug 18, giving a resilient latching effect on arm 21; in this raised position, both sound heads and their needles are out of engagement with their respective records. Swinging the cam over 180° lowers member 12, which lowers tone arm 20, and inasmuch as tone arm 21 is supported by tone arm 20, on pivot 22, tone arm 21 is simultaneously lowered, and loop 27 disengaged. This gives arm 21 a slight freedom of movement with respect to arm 20, so that each arm can be accurately positioned in its sound groove.

Affixed to the outer end of each of the parts 20 and 21 of the arm 10 is a hinge 30 and the opposite end of the hinge 30 is secured to a housing 31, which housing is adapted to receive and securely retain a sound head 32, the head carrying the usual wiring, needle and the like. The head may be secured within the housing by any suitable means such as a screw 33.

Each part 30 of the hinge also has secured thereto several threaded clamping members 34. As illustrated they are in the form of bolts and nuts. A counterweight 35 and supporting member 36 therefor are secured to the hinge parts 30 by means of the clamping members 34, the supporting members 36 having a slot 37 arranged therein to permit adjustment of the counterweight with respect to the sound head, whereby the force with which the sound head presses against the record groove through the medium of the needle may be readily and suitably varied.

The sound heads 32 may be either recording or reproducing and it is readily apparent that a recording head may be affixed to one end of the arm while a reproducing head may be fixed to the other end, or both heads may be recording or reproducing heads, as desired.

Record holders 38 each support a record 39, the record holders being driven as shown in Fig. 6 in the same rotary direction by means of a constant speed motor 40 having a double ended shaft with worm and gear driving means 41 connecting the motor to the record holders. The speed of the motor, however, may be varied if desired by a suitable control 42 such as a rheostat.

If it is desired to drive the record holders at different speeds, a schematic diagram is shown in Fig. 7, whereby a separate motor 43 may be provided to drive each record holder, these motors also having suitable speed control means 44 arranged in their power circuits.

When the cam is in the position shown in Fig. 4, the tone arm assembly including the sound heads, is in elevated or inactive position. That is, the needles are not in registry with the grooves of the records. When, however, the cam is in the position opposite to that in Fig. 4, that is, has been turned 180° to said position, the tone arm assembly will be in lowered or record-engaging position. Thus the device readily lends itself to rapid manipulation by this feature. Furthermore, in order that the proper point for starting each record may be readily reached, the moving of arm part 21 with respect to part 20 will permit the operator to place the needle at the exact desired location on each record.

When it is desired to use only one sound head, the other sound head may be pivoted 180° about the pivoted hinge 29 to rest on top of the tone arm; the other sound head may be used in this connection as a single arm arrangement.

As a modification of the instant invention, the same is not limited to one tone arm assembly, but may be incorporated within reasonable limits to embody more than one and, for example two, comprising two assemblies of two heads each. Such two arm assemblies may be provided on the same central standard. This would necessitate using a little longer arm than that illustrated and in this event one arm assembly comprising a single assembly will be slightly above the level of the arm which comprises a second assembly. Such an arrangement will serve to conserve space. The four record holders may be rotated, for example, by gearing the additional two record holders to the periphery of the first two, in order to maintain identical speeds of the four tables. The various pick-up or recording heads in the latter set-up can be independently controlled by turning them backwards or to rest positions on the tone arms if they are not all to be worked at the same time.

The push-pull principle mentioned above is brought about by the tone arm assembly being disposed at an angle to a line drawn between the axes of the record holders and drivers. The needle in the first sound head, in riding in the center of the record groove, will tend to exert a force on the tone arm moving the first head and adjacent arm end toward the center of the first record. This force simultaneously acts 10 through the arm pivot 11 to influence the other end of the tone arm and its corresponding needle to keep the latter in the center of the groove in its corresponding record. Similarly, said other needle, in riding in the groove in its record and 15 in staying in the center thereof, will transmit force through the arm pivot 11 to act on the first needle to tend to keep it in the center of the groove of its corresponding record. Thus, needle scratch is reduced and an equalization feature is induced which is described as having a push-pull principle.

Having thus described the invention, it is to be understood that changes may be made in carrying out the invention without departing from the spirit thereof and the invention is to be limited only insofar as warranted by the appended claims.

I claim:

1. A duplex tone arm for simultaneous cooperation with a pair of sound records of the disc type positioned on side by side driving tables, comprising a supporting standard positioned between said tables, a tone arm carried by said standard, a second tone arm, supported by the first tone arm, sound translating devices at the ends of each of said tone arms, and means, forming part of said supporting standard, for lowering and raising the first tone arm, and with it, the second tone arm, into and out of operative relationship with their respective records.

2. A duplex tone arm for simultaneous cooperation with a pair of sound records of the disc type positioned on side by side driving tables, comprising a supporting standard positioned between said tables, a tone arm carried by said standard, a second tone arm, movably supported by the first tone arm to have a slight degree of freedom of movement with respect thereto, sound translating devices at the ends of each of said tone arms, and means, forming part of said supporting standard, for lowering and raising the first tone arm, and with it, the second tone arm, into and out of operative relationship with their respective records.

3. A duplex tone arm for simultaneous cooperation with a pair of sound records of the disc type positioned on side by side driving tables, comprising a supporting standard positioned between said tables, a tone arm carried by said standard, a second tone arm, pivotally supported by the first tone arm on a vertical axis, to have a slight degree of freedom of movement with respect thereto, sound translating devices at the ends of each of said tone arms, and means, forming part of said supporting standard, for lowering and raising the first tone arm, and with it, the second tone arm, into and out of operative relationship with their respective records.

4. A duplex tone arm for simultaneous cooperation with a pair of sound records of the disc type positioned on side by side driving tables, comprising a supporting standard positioned between said tables, a tone arm carried by

said standard, a second tone arm supported by the first tone arm, sound translating devices at the ends of each of said tone arms, means, forming part of said supporting standard, for lowering and raising the first tone arm, and with it, the second tone arm, into and out of operative relationship with their respective records, and latching means, operative to latch the tone arms together when in raised position, and to release said arms from such latching engagement when the arms are lowered.

5. A duplex tone arm for simultaneous cooperation with a pair of sound records of the disc type positioned on side by side driving tables, comprising a supporting standard positioned between said tables, a tone arm carried by said standard, a second tone arm supported by the first tone arm, sound translating devices at the ends of each of said tone arms, and means, forming part of said supporting standard, and including a manually operated cam, operatively connected to the first tone arm, for lowering and raising the first tone arm, and with it, the second tone arm, into and out of operative relationship with their respective records.

6. A duplex tone arm for simultaneous cooperation with a pair of sound records of the disc type positioned on side by side driving tables, comprising a supporting standard positioned between said tables, a tone arm carried by said standard, a second tone arm supported by the first tone arm, sound translating devices pivotally mounted on the ends of the tone arms, and swingable into and out of operative relation

with their respective records, and means, forming part of said supporting standard, for lowering and raising the first tone arm, and with it, the second tone arm, into and out of operative relationship with their respective records.

7. A duplex tone arm for simultaneous cooperation with a pair of sound records of the disc type positioned on side by side driving tables, comprising a supporting standard positioned between said tables, a tone arm carried by said standard, a second tone arm supported by the first tone arm, sound translating devices each provided with a counterweight, and swingable on horizontal pivots, into and out of operative relationship with their respective records, and means, forming part of said supporting standard, for lowering and raising the first tone arm, and with it, the second tone arm, into and out of operative relationship with their respective records.

10 8. A duplex tone arm for simultaneous cooperation with a pair of sound records of the disc type positioned on side by side driving tables, comprising a supporting standard positioned between said tables, a tone arm carried by said standard, a second tone arm supported by the first tone arm, sound translating devices carried respectively at the ends of the tone arms, each of said devices being variably positionable longitudinally on its tone arm, and means, forming part of said supporting standard, for lowering and raising the first tone arm, and with it, the second tone arm, into and out of operative relationship with their respective records.

CHRISTIAN A. VOLF.
